IRONING BOARD

Paul N. Howard, Seattle, Wash.

Application January 2, 1934, Serial No. 704,944

3 Claims. (Cl. 68—10)

This invention relates to improvements in ironing boards, and more particularly to boards of that character having a supporting structure that is foldable against the under side of the board to make it convenient for storing the board when it is not in use; it being the principal object of the invention to provide a supporting structure having a pair of rear legs that are caused to automatically spread apart when moved from a position folded against the board to a position for supporting it, and which likewise are caused to be drawn together within the side limits of the board when moved back to the position folded against the board.

15 It is also an object of this invention to provide a supporting structure wherein the rear legs are connected with a front leg in a manner and by certain means whereby movement of the latter from a supporting position to a position folded against the board automatically effects a movement of the rear legs from their supporting position to a position folded against the board.

Another object of the invention is to provide a supporting structure that will support the board rigidly and solidly, and which may be readily and conveniently released to permit it to be collapsed and folded against the board.

Other objects of the invention reside in the details of construction and in the combination of parts and in their mode of operation, as will hereinafter be fully described.

In accomplishing these and other objects of the invention I have provided the improved details of construction, the preferred forms of which are illustrated in the accompanying drawings wherein—

Fig. 1 is a side elevation of the present board set up for use, showing in dotted lines the position of the legs while being moved between supporting position and a position folded against the board.

Fig. 2 is an under side view of the board with the front and rear legs folded against it.

Fig. 3 is a rear end view of the board; the front leg being omitted for clearer illustration.

Fig. 4 is a detail and side view of a toggle joint.

Fig. 5 is an under side view of the same.

Fig. 6 is a cross section on line 6—6 in Fig. 4.

50 Referring more in detail to the drawing—

The ironing board top or table is designated by reference numeral 1. Fixed securely to the under side of the top, near its rear end, is a cross bar 2 having downturned, opposite end portions forming mounting ears 3 and 3' for a cross

rod 4. The opposite ends of the cross rod 4 extend rotatably through perforations in the ears and terminate slightly beyond the ears.

Fixed on the opposite ends of the cross rod 4 at the outside of the ears 3 and 3' are rear legs 5 and 5' of the supporting frame structure. These legs have holes bored therethrough at their upper ends to tightly receive the ends of the cross rod 4 and the legs are held on the rod by nuts 6 threaded onto its ends. Joining legs 5 and 5' 10 slightly below the medial point, is a toggle link comprising opposite end sections 7—7' pivotally connected at their outer ends by pivot bolts 8—8' to legs 5 and 5' respectively, and with their inner ends hingedly joined by a rivet, or bolt as 15 at 9. The inner end of the toggle link section 7 is rounded radially about the axis of the rivet 9 while the end of section 7' is extended somewhat beyond the connection and there is a cap 10 secured by rivet 9 to overlie the joined ends 20 of the sections. This cap comprises the top portion 10a, as seen in Fig. 6, and has downturned opposite side flanges 10b and 10c through which rivet 9 is extended. The top portion 10a lies flatly against the top edge of the toggle section 7' and is thereby prevented from any pivotal movement relative to that section, but by reason of the round end of section 7 this section may move hingedly to permit the toggle to break upwardly as indicated in dotted lines in Fig. 3. The 30 toggle cannot break downwardly, however, beyond a definite line which is just slightly below the dead center line drawn between the pivots and the outer ends of the toggle.

Fixed to the under side of the board, flush with the rear end edge, is a cross piece 12 on which a bracket 13 is fixed centrally of the board. This bracket has slightly spaced, downturned ears 14—14' alined transversely of the board to which the upper ends of the rigid links 15—15' are pivotally attached by pivot bolts 16 and 16'. At the lower ends of these links they are connected pivotally to the sections 7—7' respectively of the toggle link by pivot bolts 17—17' located at points symmetrically spaced within and relatively close to the outer ends of the sections 7—7'.

It is observed by reference to Fig. 1 that the points of connection of the links 15—15' with the bracket 13 are in alinement parallel with the rod 4 and eccentric of the axial line of the rod, therefore, when the legs 5—5' are swung forwardly from supporting position as to the dotted line position of Fig. 1, the links 15—15' will pull upwardly on the toggle link section and will cause the toggle to break upwardly as seen in 55

dotted lines in Fig. 3; thus, to cause the lower ends of the legs 5—5' to be moved toward each other as they swing toward a position folded against the under side of the board. The arrangement is such that the legs 5—5', when in supporting position, are in divergence as seen in Fig. 3, to give lateral rigidity to the structure, but when folded against the board they are substantially parallel and disposed well within the side edges of the board, permitting storage of the board in a space substantially the width of the board.

Fixed to the under side of the board forwardly of the rear leg mounting means is a cross bar 20 having downturned opposite end portions 21 to which the upper end portions of the front leg 22 of the supporting structure are pivotally attached by pivot bolts 23.

The leg 22 comprises opposite side portions 22a and 22b as seen in Fig. 2, that are fixed together at the lower ends by bolt 24 and extend in divergence toward their upper ends. When the board is erected leg 22 extends from its point of connection with the board forwardly and downwardly to a point substantially directly below the forward end of the board. The rear legs, when erected, are inclined slightly to the rear of the vertical position. Links 25—25' joins the leg 22 with the legs 5 and 5' to limit the spreading apart of the legs at their lower ends; these links being pivotally attached by pivot bolts 26 to the leg 22 near its lower end and pivotally connected to the legs 5—5' by bolts 27 extending through the rear legs near their upper ends.

Toggle links 28 and 28' are fixed pivotally to the cross bar 21 by pivot bolts 23 and are pivotally connected at the opposite ends to the legs 5—5' at points substantially midway between the upper and lower ends by pivot bolts 30. These toggle links comprise sections 28a and 28b, pivotally joined by rivets 32. Caps 33 are associated with the joint similarly as the cap 10 described in connection with the toggle link of the rear legs. Cap 33 operates to limit the downward breaking of the links and retains the toggles rigid when the supporting structure is erected.

The rigidity of the rear legs, when the board is in use, is maintained by the toggles 28 and the rigidity of the front leg is maintained by reason of the link 25 which extends from the rear legs to the lower end portion of the front leg.

When it is desired to close the supporting structure against the board, the operator pulls upwardly on the toggle links 28 causing them to break upwardly, as toward the dotted line position shown in Fig. 1. Then, by swinging the front leg 22 upwardly and toward the under side of the board, the links 25 effect an upwardly swinging action of the rear legs 5 and 5' and the parts finally assume a position flatly against the under side of the board, as shown in Fig. 2. As the parts move to this folded position, the toggle link joining the rear legs is caused to break upwardly and the rear legs thereby are moved toward each other bringing all the supporting structure within the limits of the side edges of the board. The length of the cross bar 20 is such that it does not

interfere with the folding of the rear legs flatly against the under side of the board. Also, the links 25, which are made of flat strap iron may be twisted at certain points as indicated at 25a in Figs. 1 and 2, so that they will not interfere with the closing or folding action of the links 28.

It has been observed in devices of the prior art, boards with rear legs of this character have been provided, but they have been joined to the board through a double hinge mechanism. In the present instance, however, the cross rod 4 which mounts the rear legs, rotates in its support, but the legs have no hinging action on the rod. Therefore, when they swing from the position in Fig. 1 to the position of Fig. 2, there will be a flexing or bending of the rod 4 to accommodate the movement of their lower end portions toward each other. Therefore, I provide that the rod 4 shall be of resilient material which will permit of this flexing without any damage thereto and also makes possible the mounting of the legs 5—5' thereon in a rigid joint and avoids the difficulty and undesirability of a compound or flexible joint.

Having thus described my invention, what I claim as new therein and desire to secure by Letters Patent is—

1. The combination with an ironing board, of a supporting structure therefor including a cross rod rotatably mounted in spaced supports secured to the under side of the board in alignment transversely thereof, a pair of supporting legs fixed on the ends of said cross rod in downwardly diverging relation, a toggle connecting the legs across their lower ends and whereby they are held in divergence, rigid links pivotally connected with the toggle and with the board eccentrically of the rod, and whereby movement of the legs to a position folded against the board will cause said toggle to break and thereby draw the lower ends of the legs toward each and within the side limits of the board; said cross rod being resilient to permit of the drawing together of the legs.

2. The combination with an ironing board, of a supporting structure therefor including a resilient cross rod rotatably mounted on the board; a pair of supporting legs rigidly mounted on the ends of said cross rod in downwardly diverging relation; a toggle connecting the legs across their lower ends and whereby they are held in divergence; and rigid links pivotally connected with the toggle and with the board eccentrically of the rod, and whereby movement of the legs to a position folded against the board will cause said toggle to break and thereby draw the lower ends of the legs toward each other and within the side limits of the board and a toggle connecting the board and legs to retain them against collapse when in board supporting position.

3. In an ironing board of the type described having a pair of board supporting legs and means whereby said legs, when moved from extended diverging relation to a position against the board, are caused to be drawn together at their lower ends within the sides of the board; a resilient cross rod rotatably mounted underneath the board having said legs rigidly fixed at the ends thereof.

PAUL N. HOWARD.
